ATTORNEY

UNITED STATES PATENT OFFICE

ERNEST BOCCINO, OF NEWARK, NEW JERSEY

TOY BELLOWS AND REED

Application filed March 24, 1926. Serial No. 97,139.

This invention relates to bellows, more particularly to small types used in connection with wind operated reeds in the production of sound.

5 One object of the invention is to provide a strong and efficient bellows operated by direct compression and composed of few and simple parts.

10 Another aim is in the provision of a cylindrical type of bellows designed to be easily and rapidly assembled and which protects the ends of the spring from causing damage to the walls of the bellows casing.

15 It is a further feature to produce a bellows that is inexpensive to construct and which may be used indefinitely without deterioration.

20 These and other objects are attained by the novel construction and combination of parts hereinafter described and shown in the accompanying drawing, forming a material part hereof, and in which:—

Figure 1 is a top plan view of a preferred embodiment of the invention.

25 Figure 2 is a longitudinal sectional view taken on line 2—2 of Fig. 1.

Figure 3 is a top plan view of a slightly modified form of the device.

30 Figure 4 is a longitudinal sectional view taken on line 4—4 of Fig. 1.

Figure 5 is a plan view of another embodiment of the invention.

35 Figure 6 is a sectional view taken on line 6—6 of Fig. 5.

Figure 7 is a plan view of a further modification of the bellows.

Figure 8 is a sectional view taken on line 8—8 of Fig. 7.

40 Figure 9 is another plan view of a still further adaptation of the device.

Figure 10 is a longitudinal sectional view taken on line 10—10 of Fig. 9.

45 Figure 11 is a longitudinal sectional view of an improved reed used in connection with the bellows, drawn to a greatly enlarged scale.

Figure 12 is a transverse sectional view taken on line 12—12 of Fig. 11.

50 Throughout the several views the numeral 15 designates in general one of the heads of

the bellows, all of which are shown as cylindrical, and 16 the opposite mating head.

In Figs. 1 and 2 the heads have integrally formed with them bands or rings 17 and 18 over which is a flexible fabric strip secured by an adhesive to form an impervious cylindrical casing 19, the preferred material being ordinary commercial adhesive tape impregnated or covered with a sticky pitch or wax-like preparation that retains the fabric 55 in operative position on the rings, is sufficiently flexible and air tight to produce the desired results.

Formed in the heads 15 and 16 are openings 20 arranged in any preferred manner 65 and of such size and number as may be required, by which the device may be fastened to objects with which it is to be used.

Set in one of the heads, as 15, is a reed 21 open at one end to the atmosphere and at 70 the other to the interior of the bellows as is customary.

A coarsely wound spiral compression spring 22 is disposed within the casing, its ends abutting the respective heads and are 75 protected from puncturing or otherwise injuring the fabric wall by reason of the guiding rings 17 and 18.

In the type shown in Figs. 3 and 4 the heads are made separately from the rings 80 which are however firmly secured together, the difference being one of construction only.

In Figs. 5 and 6, the head 15 is held within and at about the center of length of a cylindrical band 24 which thus extends at 85 both ends beyond the head, protecting the reed from damage by coming in contact with objects which might tend to displace or injure it, the lower head being of the construction shown in Figs. 1 and 2.

Figs. 7 and 8 show merely that the upper head 15 is held in a reversed position relative to the casing and lower head, the rings 17 and 18 being of integral type and other parts as before described.

In Figs. 9 and 10 the head 15 is formed with a cylinder 25 adapted to slidingly or telescopically engage within another cylinder 26 formed on the head 16.

In this case the flexible fabric casing ele- 100

ment 27 is secured only adjacent its marginal edges, as at 28 and 29 to the respective cylinders 25 and 26 near their heads.

Thus the casing controls the opening or distance between the heads and also prevents the leakage of air from the cylinders, which obviously are loosely fitted.

The heads, rings and cylinders may be made of suitable thick paper or of metal as may be desired, the main novelty residing in the manner of applying the flexible casing, which, as indicated, is taken from a strip of suitable material and cut of such length as to overlap at its ends.

In the construction of reeds of the types used in connection with bellows, it is customary to wrap the reed body 21 and vibratable tongue 30 with a fine thread and thereafter wind a strip of paper or the like over the threads before inserting in the opening in the head, at which time, in order to prevent leakage of air and consequent failure of the reed to operate, it is necessary to use melted paraffine or the like to provide an air tight structure.

In the present case the body and tongue are wrapped with a strip of adhesive tape 31 of the nature described, forming a close fitting joint impervious to air and requiring no securing means, the use of such tape constituting a material improvement.

While certain preferred embodiments of this device have been shown and described, it will be understood that changes in the form, arrangements, proportions, sizes and details thereof may be made without departing from the scope of the invention as defined in the appended claims.

Having thus described my invention, what I claim as new and desire to secure by Letters Patent, is:—

1. A toy bellows comprising a pair of rigid circular heads having flanged rings at their edges, a helical spring pressing said heads apart, said spring being held in operative position by said rings, and a strip of adhesive tape applied in the manner of a band to said rings.

2. A toy bellows comprising a pair of rigid circular heads having flanged rings at their edges, one of said heads having a reed inserted therethrough, said reed being wound with an adhesive tape to form an air tight joint, an expansion spring loosely confined by said rings to press said heads apart, and a casing composed of a strip of flexible impervious material secured by a viscid adhesive on the outer surfaces of said rings.

Signed at New York, in the county of New York and State of New York, March, A. D. 1926.

ERNEST BOCCHINO.
